UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,209,847.

Specification of Letters Patent. Patented Dec. 26, 1916.

Application filed January 10, 1913. Serial No. 741,164.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

My invention relates to typographical machines, such for instance as the linotype machines disclosed in Letters Patents of the United States to John R. Rogers, No. 848,771 and No. 930,693, wherein a number of fonts or sets of matrices representing different styles of type are employed, in such manner that any font may be brought into action at will, and so that a line may be produced with the face represented by the matrices in any one magazine, or with a combination of faces represented by matrices in two or more magazines. To this end is provided a series of superposed magazines, in combination with movable means for directing the matrices from the selected one to a common assembling mechanism, and also escapement actuating devices adjustable or shiftable bodily in such manner as to coöperate with the escapements of one magazine or another, as demanded.

In machines of the kind specified, the movable means for directing the matrices from the selected magazine to the assembling mechanism, and the means for shifting the escapement actuating devices from one magazine to another, are manually operated, and ordinarily by the manipulation of hand levers.

It is one of the principal objects of my invention to provide power-driven means for effecting the shifting and adjusting operations described, thereby obviating the manual effort now necessary, and insuring greater speed and the more accurate movement and registration of the parts. To this end, I have devised certain mechanism which will now be described and finally pointed out in the claims.

In the accompanying drawings, I have shown my invention in preferred form and by way of example, and as applied to the specific style of machines designated, but obviously many variations and alterations therein, and in its mode of application, will be possible and still be comprised within its

spirit. Generally speaking, I desire it to be understood that I do not limit myself to any specific form or embodiment, except in so far as such limitations are specified in the claims.

Referring to the drawings: Figure 1 is a front view, partly broken away, of a portion of the machine, having my invention applied thereto; Fig. 2 is an enlarged side view, partly in section, on the line 2—2 in Fig. 1; Fig. 3 is a similar view, showing certain of the parts in different positions; Fig. 4 is a horizontal sectional view, taken substantially on the line 4—4 in Fig. 1; Fig. 5 is a longitudinal section through the clutch mechanism; Fig. 6 is a section, taken substantially on the line 6—6 in Fig. 2; and Fig. 7 is a detail of the clutch, etc., as indicated by the line 7—7 in Fig. 5.

As in the Rogers patents previously mentioned, the matrices X are stored in a plurality of superposed magazines A, and their delivery is controlled by the connected escapements A¹ in the usual manner. For purposes of illustration, only two such magazines are shown, but obviously their number may be increased to any desired extent. The escapements of the magazine in operation are directly actuated by the members B, which in turn are controlled by the pivoted levers B¹ and reeds B² from the keyboard B³. As the matrices are released from the magazines, they pass downward through the throat or bridge C to the belt C¹, by which they are delivered to the other assembling devices. The throat C and the escapement actuating members B are arranged to be shifted from one magazine to another by the power-driven devices hereafter to be described.

The throat C and members B are mounted on the transverse frame D, arranged to slide vertically in the pivoted frame M, and provided at its opposite lower corners with depending arms D¹ carrying rollers D², which engage the cam grooves E¹ in the compound cams E, whereby the frame D may be elevated or lowered to register the parts with the selected magazine. The actuating members B are also arranged in the frame D so as to have two relative movements with respect thereto, to wit, a longitudinal one, imparted to them from the lever B¹ for the actuation of the escapements A¹, and a lateral one, whereby they are shifted edge-

wise in the frame to disengage them from and engage them with the escapements A¹ and levers B¹. The latter or lateral movement of the members B is effected by eccentricities F, a pair of such eccentricities being employed in connection with each member B, and located in longitudinal slots therein, which eccentricities in their respective series are mounted upon the transverse rock shafts 10 F¹ journaled in the frame D. At each end of both of the shafts F¹ is mounted a rock arm F², connected at its extremity to the sliding piece F³, which at its lower end is provided with a roller F⁴ engaging in the 15 cam groove E² of the compound cam E, previously referred to, the two grooves E¹, E², being located at opposite sides thereof. The cam grooves E² are so shaped that when the cams are rotated, and acting through the 20 connections just described, the shafts F¹ and the eccentricities F thereon will be turned so as to disengage the actuating members B from the escapements of the magazine in operation, and when the parts are brought 25 into registration with another magazine, the shafts and eccentricities will be rocked in the opposite direction to restore the actuating connection.

The compound cams E at the opposite 30 corners of the frame D are mounted upon the transverse shaft E³, which is journaled in the frame M, and rotated by power-driven connections at the will of the operator, in the manner subsequently to be described. It will be noted that the cam grooves E¹ and E² are of the same configuration and substantially parallel, except that the latter, at points corresponding to the 35 positions of rest, is formed with the depressions E¹⁰. When the parts are at rest, they assume the position illustrated in Fig. 2, wherein the lower magazine A is shown in operation. When the shaft E³ is rotated, the first effect is to cause the rollers F⁴ to move 40 out of the depressions E¹⁰, thereby shifting the slides F³ upwardly with relation to the frame D, and consequently breaking the escapement actuating connection in the manner previously indicated. The two cam 45 rollers D² and F⁴ now travel in substantial parallelism, and due to the configuration of the cam grooves, the frame D and the parts carried thereby travel together and without further relative movement between them, 50 until they are located in proper operative relation to the new magazine. In the specific form illustrated, this result occurs when the shaft E³ and the cams E have been rotated through an angle of 180°, at which time other depressions E¹⁰ in the cam grooves E² present themselves in relation to the rollers F⁴, whereupon the slides F³ descend relatively to the frame D, and the members B are brought into engagement 55 with the selected escapements A¹ and the

actuating levers B¹, in the manner set forth in the said Rogers patents.

On the shaft E³ is mounted the sprocket wheel G, connected by the chain G¹ to a sprocket wheel G², revolvably mounted on the stud shaft G⁴; and connected to the sprocket wheel G², is the clutch member G³, arranged to be actuated by the clutch member H³ (see particularly Figs. 4 and 5). The clutch member H³ is mounted upon and 70 operated by the shaft H², which is constantly rotated in any desired manner, as for instance by gearing H¹ from the power shaft H. The clutch member H³ is capable of a slight longitudinal movement with reference to the shaft H², it being preferably connected thereto by a pin-and-slot connection H⁴ between its hub H⁵ and the shaft. Mounted upon the hub H⁵ is the collar J, which thus partakes of the longitudinal 80 movement of the clutch member H³, but is held against rotation, preferably by the rods J¹, projecting therefrom and through corresponding cylindrical recesses or bores formed in the stationary journal H¹⁰. A 85 coiled spring J², interposed between the hub H⁵ and journal H¹⁰, normally presses the clutch member H³ toward the clutch member G³. This pressure is resisted and controlled by the spring-pressed pivoted hook 90 J⁶, which normally engages with the catch J⁵ connected to the collar J. The hook J⁶ may be disengaged from the catch J⁵ by the key K and connecting rod K¹, the key K being located within convenient reach of the 95 operator and preferably in proximity to the keyboard. The collar J is provided with two laterally projecting fingers J¹⁰ formed with inclined surfaces, and adapted to be engaged by similar projecting fingers G¹⁰ 100 formed on the clutch member G³, when the latter has been actuated, or, in the illustrated instance, when it has been rotated through an angle of substantially 180°.

The operation of the parts will now be 110 clearly understood: The clutch members stand normally in the positions indicated in Fig. 5. When the key K is operated, the hook J⁶ is elevated, and the spring J² presses the clutch member H³ into engagement with the clutch member G³, and as a result of this connection, the shaft E³ and cams E are 115 rotated, to effect the breakage of the escapement actuating connections, the shifting of the frame D and throat C to another magazine, and finally the restoration of the escapement actuating connections in the new 120 position, all in the manner previously described; which cycle of operation is accomplished by the rotation of the parts through an angle of 180°, in the particular instance shown in the drawings. At about this time, the fingers G¹⁰ on the clutch member G³ contact with the fingers J¹⁰ on the collar J (see Fig. 4), and due to the engagement of the 125 130

inclined surfaces thereon, the collar J and clutch member H³ are forced rearwardly to a sufficient extent to break the clutch connection, and they are then held in this inactive position by the reengagement of the hook J⁶ with the catch J⁵. The parts now come to rest, with the assembling devices in operative relation to the new magazine, and remain there until the key K is again pressed by the operator, when the opposite or a corresponding sequence of operations is effected.

Referring to Figs. 4 and 6, it will be noted that the shaft E³ is journaled in the frame M, and in order to allow the latter to be swung outwardly about the pivot M¹ in the manner disclosed in the said Rogers patents, a stud E¹³ is provided, in line with the shaft E³, but mounted on the stationary framework. The sprocket wheel G is splined to the shaft E³, so that it may be moved laterally therefrom onto the stationary member E¹³, when desired, as indicated by dotted lines in Fig. 4, to permit the unimpeded opening of the frame M, by relieving it from the holding effect of the chain G¹.

Having thus described my invention, its construction and mode of operation, what I claim and desire to secure by Letters Patent of the United States is, as follows:

1. In a typographical machine, the combination of a plurality of stationary magazines, an assembling throat or switch to receive the matrices from the magazines, a finger key mechanism, and power driven means, acting under the control of the finger key mechanism, to shift the assembling throat into operative relation to one or another of the magazines.

2. In a typographical machine, the combination of two stationary magazines, an assembling throat or switch to receive the matrices from the magazines, a single finger key, and power driven means acting in response to the repeated actuations of the key to shift the assembling throat into operative relation to first one magazine and then the other alternately.

3. In a typographical machine, the combination of a plurality of stationary magazines each provided with a series of escapements, a single series of relatively adjustable actuating connections, a finger key mechanism, and power driven means, acting under the control of the finger key mechanism, to shift the actuating connections into operative relation to the escapements of one or another of the magazines.

4. In a typographical machine, the combination of two stationary magazines each provided with a series of escapements, a single series of relatively adjustable actuating connections, a single finger key, and power driven means, acting in response to the repeated actuations of the finger key, to shift the actuating connections into opera-

tive relation to the escapements of the two magazines alternately.

5. In a typographical machine, the combination of a plurality of stationary magazines each provided with a series of escapements, an assembling throat or switch to receive the matrices from the magazines, a single series of actuating devices, a movable supporting frame carrying the assembling throat and actuating devices, a finger key mechanism, and power driven means, acting under the control of the finger key mechanism, to shift the supporting frame relatively to the magazines so as to locate the assembling throat and the actuating devices in operative relation to one or another thereof.

6. In a typographical machine, the combination of two magazines each provided with a series of escapements, an assembling throat or switch to receive the matrices from the magazines, a series of actuating devices, a movable supporting frame carrying the assembling throat and actuating devices, a single finger key, and power driven means acting in response to the repeated actuations of the finger key to shift the supporting frame relatively to the magazines so as to locate the assembling throat and actuating devices first in operative relation to one and then in operative relation to the other alternately.

7. In a typographical machine, the combination of a plurality of magazines, an assembling throat or switch to receive matrices from the magazines, power driven means for shifting one of said parts relatively to the other to establish an operative relation between the assembling throat or switch and one or another of the magazines, and a finger key mechanism controlling the operation of said power driven means.

8. In a typographical machine, the combination of two magazines, an assembling throat or switch to receive matrices from the magazines, power driven means acting by repeated operations to shift one of said parts relatively to the other to establish an operative relation between the assembling throat or switch and first one magazine and then the other alternately, and a single finger key controlling the operation of said means.

9. In a typographical machine, the combination with a plurality of magazines and an assembling throat or switch, the said parts being movable one relatively to the other to establish an operative relation between the assembling throat or switch and one or another of the magazines, of power driven means acting by a given cycle of operation to effect such relative movement of the parts, finger key mechanism for initiating the action of said means, and automatic means for disconnecting the power

4
driven means after they have completed their cycle of operation.

10. In a typographical machine, the combination with a plurality of magazines and an assembling throat or switch, the said parts being movable one relatively to the other to establish an operative relation between the assembling throat or switch and one or another of the magazines, of power driven means acting by a given cycle of operation to effect such relative movement of the parts, means for initiating the action of said power driven means, and automatic means for rendering the power driven means inactive after they have completed their cycle of operation.

11. In a typographical machine, the combination with a plurality of magazines and an assembling throat or switch, the said parts being movable one relatively to the other to establish an operative relation between the assembling throat or switch and one or another of the magazines, of power driven means including a clutch for effecting such relative movement of the parts, means for engaging said clutch, and automatic means for disengaging it when the operative relation has been established between one of the magazines and the assembling throat or switch.

12. In a typographical machine, the combination of a plurality of stationary magazines, an assembling throat or switch to receive the matrices from the magazines,

power driven means acting by a given cycle of operation to shift the assembling throat into operative relation to one or another of the magazines, finger key mechanism for initiating the action of said means, and automatic means for disconnecting the power driven means after they have completed their cycle of operation.

13. In a typographical machine, the combination of a series of escapement actuating members, a movable supporting frame, mechanism for moving the supporting frame to different operative positions, and means actuated by the initial operation of said mechanism for shifting the escapement actuating members laterally with respect to the supporting frame, for the purpose described.

14. In a typographical machine, the combination of a series of escapement actuating members, a movable supporting frame, rotary mechanism for moving the supporting frame to different operative positions, and means actuated by the initial rotation of said mechanism for shifting the escapement actuating members laterally with respect to the supporting frame, for the purpose described.

In testimony whereof I affix my signature in presence of two witnesses.

DAVID S. KENNEDY.
